RAIL ANCHOR

Rolandis A. Blair, Columbia City, Ind.

Application February 6, 1933, Serial No. 655,337

18 Claims.

(Cl. 238—329)

My invention relates to rail anchors of the type adapted to be clamped on the flange of a rail and adapted by engagement with a cross tie or other fixed portion of a track to hold the rail against movement longitudinally thereof. It is the object of my invention to provide an improved form and arrangement of parts in a device of this character by reason of which an improved gripping effect may be had on the rail.

It is one of the objects of my invention to provide an improved arrangement with respect to the application of the anchor to a rail whereby the anchor is made effective for gripping a rail regardless of slight discrepancies or tolerances in the dimensions of the rail due to wear of the rolls by which the rails are produced or to any other cause. To this end, it is one of the objects of my invention to provide an improved connection between the abutment member and the transverse bar member of my improved device, comprising preferably a part carried by or forming a portion of the abutment member and adapted to yield transversely of the rail with respect to said abutment member but to resist strongly any tendency for such transverse movement, and arranged so that when said part is in its normal position the anchor shall have an effective grip on a rail of a predetermined minimum size and whereby when said part is moved transversely out of normal position by the application of heavy pressure thereon the effective length of the bar member extended beyond the abutment member is increased slightly for holding the abutment member in effective gripping relation to a rail of slightly greater width or slightly greater thickness. It is one of the objects of my invention to provide a yielding connection of this type between the abutment member and the transverse bar member by the use of an arm positioned on the abutment member so as to extend longitudinally of the rail and preferably free at one end, the arrangement preferably being such that a shifting of the bar member may be effected transversely of the rail with respect to the abutment member for varying the effective length of said bar member without substantially changing the relative positions of the gripping jaws of said abutment member with respect to each other.

It is one of the objects of my invention to provide an improved arrangement of gripping parts comprising a jaw member adapted to engage one edge of the flange of a rail together with means adapted to cooperate with said jaw

member whereby said member is tilted about an axis extending transversely of the rail as said member is forced into position on the flange for giving said member a shackle or lever grip on the top and bottom faces of said flange.

It is another object of my invention to provide an improved arrangement of resilient means for connecting a transverse bar to an abutment member in a device of this type by reason of which the bar is free to swing downwardly to the necessary extent for permitting an upwardly extending retaining lug on said transverse bar to have the desired snap engagement with the opposite edge of the rail flange due in part at least to a yielding of the engaged portion of the abutment member without the necessity that all of the distortion in a vertical direction shall take place in said transverse bar member, serving thus to distribute the deformation so as to cut down the probability of permanent distortion at any point. To this end, it is one of the objects of my invention to provide an arrangement of this sort in which the part of the abutment member having engagement with the transverse bar member is yieldable with respect to the remainder of the abutment member so as to be capable of being distorted for permitting the desired angular movement of the transverse bar member as a whole. It is one of my objects to provide an arrangement of this type in which the transverse movement of the yielding engaged portion of the abutment member normally occurs without any tendency thereby to force the transverse bar member to swing downwardly.

It is another object of my invention to improve devices of this type in sundry details hereinafter pointed out. The preferred means by which I have accomplished my several objects are illustrated in the accompanying drawing and are hereinafter specifically described. That which I believe to be new and desire to cover by Letters Patent is set forth in the claims.

In the drawing,—

Fig. 1 is an outside face view of my improved abutment member with the transverse bar member engaged therewith, the transverse bar member being shown in vertical section;

Fig. 2 is a view from the same point, but with the transverse bar member in end elevation, and with the anchor in operative gripping position on a rail, a fragmentary portion of which is shown;

Fig. 3 is a vertical section taken at line 3—3 of Fig. 2;

Fig. 4 is a vertical sectional view taken at line 4—4 of Fig. 1, but showing the parts in their initial preliminary position upon a rail; and

Fig. 5 is a top plan view of the left-hand end portion of the transverse bar member as shown in Fig. 3.

Referring now to the several figures of the drawing, in which corresponding parts are indicated by the same reference characters, 15 indicates a rail supported in a track by a series of cross ties 16, only one of which is illustrated. An abutment member 17 is mounted upon the 15 flange 18 of the rail 15 in contact with the cross tie 16, being held in position upon the flange by a transverse bar member 19.

As is clearly shown in Fig. 1, the abutment member 17 is in the form of a U made of metal bent or pressed into form, being preferably made of spring steel. The abutment member as shown comprises a plate portion 20 forming one leg portion of the U, a bar portion 21 at right angles to the plate 20 and forming the cross bar 25 of the U, and a plate portion comprising two parts 22 and 23 located opposite to the plate 20 and forming the other leg portion of the U, the parts 22 and 23 being connected together by means of a reversely bent arm portion 24 in the form of a loop open at one end, all of the parts 20, 21, 22, 24 and 23 in the arrangement shown being formed integrally with each other from a single strip of metal. The plate portions 20 and 23 are provided at their side edges with oppositely disposed notches or openings 25 which are adapted to have a working fit upon the flange 18 of the rail upon which the anchor is designed to be effective.

My improved cross bar member 19 is provided 40 at one end with a turned back end portion or arm 26 and is provided at its opposite end with an upwardly extending arm or lug 27. The bar 19 and arms 26 and 27 are formed integrally with each other, preferably of spring steel bent or pressed into form. As is best shown in Fig. 5, the return bend portion connecting the arm 26 with the body 19 of the bar is disposed at a slight angle from the transverse, so as to give the loop formed by the bar 19 and the arm 26 50 a slightly greater effective length at one side edge than at the other.

The bar 19 and the turned back arm portion 26 are of a width corresponding to the distance between the side plate portion 20 at one side of the bar and the side plate 22—23 at the opposite side. Prior to application of the anchor to a rail, the transverse bar member is to be connected with the abutment member by the engagement of the turned back arm 26 about the loop or arm 24 of the abutment member. The spacing of the arm 26 from the body portion of the bar 19 is normally less than the vertical thickness of the arm 24 of the abutment member, so that it is necessary that some little pressure be applied for forcing the bar member into position as shown in Fig. 1, such operation serving to spread the arm 26 outwardly with respect to the body of the bar 19 so as to bring such arm 26 substantially into parallelism with the body of the bar. In such engaged position as shown in Fig. 1, the arm 26 presses upwardly upon the loop 24 of the abutment member at the point 28 as shown in Fig. 1, and the bar 19 presses downwardly upon said loop 24 at the point 29 as shown in said figure, whereby there

is a tendency for the bar member to rotate slightly in clockwise direction in Fig. 1. This tendency for the bar member to rotate or roll about an axis extending longitudinally of said bar member is overcome more or less completely by the engagement of the edges of the bar 19 and the arm 26 with the side plate portions of the abutment member which resist strongly the pressure tending to spread them apart as would be necessary for permitting such a rolling movement of the transverse bar member. The pressure of the abutment member upon the edges of the bar 19 and arm 26, and the pressure of the bar 19 and arm 26 upon the top and bottom faces of said arm 24 are sufficient for holding the abutment member and the transverse bar member yieldingly by friction in engaged position as shown in Fig. 1 so as to be capable of being shipped and handled as a unit ready for application to a rail.

When it is desired to apply the anchor to the rail for which the anchor is designed, the device is first placed in position as shown in Fig. 4, with the notches 25 of the side plates of the abutment member engaging the flange of the rail at one side, and with the lug 27 engaging the bottom face of the rail at a short distance from the opposite edge of the flange. In this position, the notches 25 are partially blocked by the body portion 19 of the cross bar member which is held in slightly elevated position with respect to the abutment member by reason of the oblique position of the arm 24 of the abutment member. In this position of the parts, the end portion of the arm 26 engages lightly with the cross bar portion 21 of the abutment member.

Pressure is then applied upon the return bend portion of the transverse bar member, by the use of a maul or otherwise, for forcing the transverse bar member toward the right in Fig. 4. As the parts move toward the right in said figure, the body portion 19 of the cross bar member is forced downwardly by the flange of the rail entering the notches 25, serving to swing the arm 24 from its oblique position as shown in Fig. 1 to a substantially horizontal position as shown in Fig. 2. This downward movement of the arm 24 and the transverse bar member serves to press the end of the arm 26 strongly into engagement with the bottom cross bar 21 of the abutment member, whereby thereafter the arm 26 is held against swinging downwardly with respect to the body portion 19. As the pressure is applied upon the device for forcing it into position on the rail, the lateral pressure between the outside loop portion of the transverse bar member and the inside loop portion 24 of the abutment member increases substantially as the play between the parts is taken up, serving to move the transverse bar member toward the right in Fig. 4 with respect to the arm or loop 24 and also to move said transverse bar member and said engaged arm portion 24 of the abutment member together toward the right in said Fig. 4 for permitting the lug 27 to snap into engagement with the edge of the flange as shown in Fig. 3. Such transverse swinging movement of the arm 24 upon continued movement of the transverse bar member toward the right in Fig. 4 is assured by reason of the fact that the engaging loop of the transverse bar member is shorter at the side engaging the free end of the arm 24 than it is at the opposite side of said transverse bar

member, as is explained above, so that initially said loop has effective engagement with said arm for applying transverse pressure thereon only at said free end portion of said arm 24.

- 5 In case the flange 18 of the rail happens to be of about the maximum size such as is produced by a badly worn set of rolls, it may be found necessary that the arm 24 be pressed some little distance toward the right in Fig. 4 for permitting the lug 27 to snap into engaging position; in extreme cases bringing the full length of the arm 24 into effective engagement with the end of the encircling loop.

By reason of the fact that the loop 24 is free to move transversely of the rail during the operation of applying the anchor to a rail, taken with the fact that the arm or loop 24 is subject to a slight distortion by a twisting action when heavy pressure is applied downwardly on the bar 19, the distortion of the body portion 19 of the transverse bar member necessary for carrying the lug 27 past the edge of the flange of the rail is limited and is distributed in such way as to prevent any permanent distortion of any of 20 the parts at any point. The arrangement is such that the transverse bar member by its engagement about the arm 24 and its engagement through the lug 27 with the opposite edge portion of the flange is adapted to hold the abutment member strongly in operative gripping position upon a rail of the minimum size to be expected, with the arm 24 standing in normal position transversely of the rail with respect to the remainder of the abutment member and 30 strongly resisting any movement transversely of the rail from such normal position. The resiliency is such, however, that the device can be applied readily without permanent distortion upon the maximum size of rail to be expected, the effective length of the transverse bar member extended beyond the abutment member being capable of variation by transverse movement of the arm 24 to the extent necessary for meeting any probable requirements.

As will be readily appreciated by an inspection of Fig. 2, the plate 23 in its applied position upon a rail stands in slightly tilted position by reason of the downward swinging movement 50 of the arm 24 in the course of application of the device to a rail, serving in such tilted position to apply a very strong shackle or lever grip upon the top and bottom faces of the flange of the rail. It will be appreciated also that when the arm 24 is swung transversely of the rail to a slight extent for permitting the transverse bar member to have effective holding engagement with the rail the plate 23 is given a slight rotary movement about a vertical axis, 55 this being effected without substantially changing the gripping effect on the rail.

As is clearly shown in Fig. 4, the transverse bar member 19 normally has a slight upward bend at an intermediate point therealong,—at 60 the point 30 in said Fig. 4,—for increasing the assurance that the lug 27 will be maintained in operative engagement with the flange. If at any time heavy pressure on the side plate 20 at its lower end portion should have a tendency to close the loop 24 between the side plate portions 22 and 23, at the same time upward pressure would be applied on the arm 26 through the bottom bar portion 21 for correspondingly 70 closing the loop of the transverse bar member,

thus preventing any loosening of one loop on the other. Such upward pressure on the arm 26 due to heavy pressure between the tie 16 and the side plate 20 would also have a distinct tendency to swing the transverse bar member as a whole in counter-clockwise direction in Fig. 3 for pressing the transverse bar member tightly against the bottom face of the rail and effectively overcoming any possible tendency for disengagement of the lug 27 from the edge of the flange.

By reason of my construction, in which the bar 19 and lug 27 are tightened against the rail as the pressure on the anchor increases, a very strong shackle or lever grip is effected on 15 the side edges or faces of the flange whereby the rail is held very firmly in position against movement longitudinally with respect to the tie.

As will be appreciated from a study of my construction, when the arm 24 is moved out of 20 normal position on the abutment member by pressure on the arm in a directly transverse direction with respect to the rail, the arm is swung about a vertical axis without any rolling or twisting motion of the arm about an axis extending longitudinally of the rail, such sidewise swinging movement of the arm accordingly having no tendency to cause any downward swinging movement of the transverse bar member 19.

I have found in practice that one of my improved devices is capable of being applied to advantage to rails of slightly varying dimensions; that the device is capable of being applied to advantage to the rail for which it is designed without danger of permanent distortion 35 of the parts; and that the device is very effective for preventing longitudinal movement of the rail upon which it is properly applied.

While I prefer to employ the form of device as shown in my drawing and as above described, it is to be understood that my invention is not limited to the form shown except so far as the 40 claims may be so limited by the prior art.

I claim:

1. In a rail anchor, the combination of an abutment member adapted to grip the flange of a rail and comprising a part extending longitudinally of the rail and movable yieldingly about a vertical axis transversely of the rail with respect to the remainder of the abutment member but adapted strongly to resist such transverse movement, and a transverse bar member adapted by engagement with said yieldingly movable part and with the edge of the flange at the opposite side of the rail to hold said abutment member strongly in operative gripping position on the rail, said bar member being of such effective length as to hold the abutment member in operative position on a rail of a predetermined minimum size with said yieldingly movable part in substantially normal position and to hold said abutment member in operative position on a rail of slightly greater size with said yieldingly movable part moved transversely of the rail slightly out of normal position.

2. In a rail anchor, the combination of an abutment member adapted to grip the flange of a rail and comprising an arm on said abutment member with one end free so as to be movable yieldingly about a vertical axis transversely of the rail but adapted strongly to resist such transverse movement, and a transverse bar member adapted by engagement with said arm and with the edge of the flange at the opposite side of the rail to hold said abutment member

strongly in operative gripping position on the rail, said bar member being of such effective length as to hold the abutment member in operative gripping position on a rail of a predetermined minimum size with said arm in substantially normal position and to hold said abutment member in operative gripping position on a rail of slightly greater size with said arm moved transversely of the rail slightly out of normal position.

3. In a rail anchor, the combination of an abutment member adapted to grip the flange of a rail and comprising an arm in the form of a loop in substantially horizontal position on said abutment member and adapted to swing yieldingly about a vertical axis transversely of the rail but adapted strongly to resist such transverse movement, and a transverse bar member adapted by engagement with said arm and with the edge of the flange at the opposite side of the rail to hold said abutment member strongly in operative gripping position on the rail, said bar member being of such effective length as to hold the abutment member in operative gripping position on a rail of a predetermined minimum size with said arm in substantially normal position and to hold said abutment member in operative gripping position on a rail of slightly greater size with said arm swung transversely of the rail slightly out of normal position.

4. In a rail anchor, the combination of an abutment member adapted to grip the flange of a rail and comprising a part yieldingly movable transversely of the rail with respect to the major portion of the abutment member but adapted strongly to resist such transverse movement, such yieldingly movable part having a bearing face extending longitudinally of the rail, and a transverse bar member having a loop at one end adapted by engagement of said loop with said yieldingly movable part of the abutment member at one side of the rail and by engagement with the edge of the flange at the opposite side of the rail to hold said abutment member strongly in operative gripping position on the rail, said yieldingly movable part and said loop being so arranged with respect to each other that they have effective engagement with each other for applying pressure transversely of the rail from one to the other at only one side portion of the transverse bar member when said yieldingly movable part is in its normal position on the abutment member.

5. In a rail anchor, the combination of an abutment member adapted to grip the flange of a rail and comprising an arm on said abutment member with one end free so as to be movable yieldingly transversely of the rail but adapted strongly to resist such transverse movement, and a transverse bar member having an end portion turned backwardly on the bar for forming a loop adapted to engage about the arm on said abutment member, said bar member being adapted by engagement with said arm and with the edge of the flange at the opposite side of the rail to hold said abutment member in operative gripping position on a rail, said loop having its bearing portions so positioned that when said arm is standing in normal position on the abutment member said loop has effective engagement with said arm for applying transverse pressure thereon only at the free end portion of the arm.

6. In a rail anchor, the combination of an abutment member in the form of a U both legs of which are adapted to grip the flange of a rail

and comprising an arm in the form of a loop formed integrally with one of the legs of the U so as to extend longitudinally of the rail toward the other leg and being open at the end portion of the loop adjacent to the leg with which it is formed, and a transverse bar member adapted by engagement with said loop and with the edge of the flange at the opposite side of the rail to hold said abutment member strongly in operative gripping position on the rail, said bar member being of such effective length as to hold the abutment member in operative gripping position on a rail of a predetermined minimum size with said loop in substantially normal position and to hold said abutment member in operative gripping position on a rail of slightly greater size with said loop swung transversely of the rail against the resiliency of said arm slightly out of normal position.

7. In a rail anchor, the combination of an abutment member in the form of a U both legs of which are adapted to grip the flange of a rail and comprising an arm in the form of a loop formed integrally with one of the legs of the U so as to extend longitudinally of the rail toward the other leg and being open at the end portion of the loop adjacent to the leg with which it is formed, and a transverse bar member having an end portion turned backwardly on the bar for forming an engaging loop adapted to engage about the arm on said abutment member, said bar member being adapted by engagement with said arm and with the edge of the flange at the opposite side of the rail to hold said abutment member in operative gripping position on a rail, said engaging loop on the transverse bar member having its bearing portions so positioned with respect to said arm that when said arm is standing in normal position on the abutment member said engaging loop has effective engagement with said arm for applying transverse pressure thereon only at the free end portion of the arm, said bar member being of such effective length as to hold the abutment member in operative gripping position on a rail of a predetermined minimum size with said arm in substantially normal position and to hold said abutment member in operative gripping position on a rail of slightly greater size with said arm swung transversely of the rail against the resiliency of said arm slightly out of normal position.

8. In a rail anchor, the combination of an abutment member in the form of a U both legs of which are adapted to grip the flange of a rail, and a transverse bar member adapted by engagement with said abutment member and with said flange to hold said abutment member in operative gripping position on the flange, the engagement between said transverse bar member and said abutment member being effected through the medium of a turned back end portion of said bar providing a loop engaging about a portion of the abutment member extending longitudinally of the rail and thereby normally holding said bar member up in operative position with respect to the rail but adapted to yield slightly upon application of the anchor to a rail for permitting the transverse bar member to swing downwardly slightly for movement transversely of the rail into operative gripping relation thereto.

9. In a rail anchor, the combination of an abutment member adapted to grip the flange of a rail and comprising a comparatively resilient

- portion extending longitudinally of the rail, and a transverse bar member adapted by engagement with said abutment member and with said flange to hold said abutment member in operative gripping position on the flange, the engagement between said transverse bar member and said abutment member being effected through the medium of a turned back end portion of said bar providing a loop adapted normally by engagement about said resilient portion of the abutment member to hold said bar member yielding up in operative position with respect to the rail. 10
10. In a rail anchor, the combination of an abutment member adapted to grip the flange of a rail at one side thereof, and a transverse bar member adapted by engagement with said abutment member and with said flange to hold said abutment member in operative gripping position on the flange, the engagement between said transverse bar member and said abutment member being effected through the medium of a turned back end portion of said bar providing a loop engaging about a portion of the abutment member and bearing at its outer face on another portion of said abutment member by which the loop is held from spreading vertically. 15
11. In a rail anchor, the combination of an abutment member adapted to grip the flange of a rail at one side thereof, and a transverse bar member adapted by engagement with said abutment member and with said flange to hold said abutment member in operative gripping position on the flange, the engagement between said transverse bar member and said abutment member being effected through the medium of a turned back end portion of said bar providing a loop engaging about a portion of the abutment member, said loop when the anchor is being applied into operative position on a rail being interposed between the rail and another portion of the abutment member by which said loop is held from spreading vertically. 20
12. In a rail anchor, the combination of an abutment member adapted to grip the flange of a rail at one side thereof, and a transverse bar member adapted by engagement with said abutment member and with said flange to hold said abutment member in operative gripping position on the flange, the engagement between said transverse bar member and said abutment member being effected through the medium of a turned back end portion of said bar providing a loop engaging about a portion of the abutment member and bearing at its outer face on another portion of said abutment member by which the loop is held from spreading vertically, the arrangement being such that the abutment member has a tendency by upward pressure on said turned back end portion on said bar to swing the body of the bar member more tightly against the rail when heavy pressure is applied on said abutment member transversely of the rail in use. 25
13. In a rail anchor, the combination of an abutment member adapted to grip the flange of a rail and comprising an arm on said abutment member and extending longitudinally of the rail with one end free so as to be movable yieldingly with respect to the remainder of the abutment member but adapted strongly to resist such movement, and a transverse bar member adapted by engagement with said arm and with the edge of the flange at the opposite side of the rail to hold said abutment member strongly in operative gripping position on a rail, the engage- 30
- ment between said transverse bar member and said abutment member being effected through the medium of a turned back end portion of said bar providing a loop engaging about said arm and so arranged as normally to hold said transverse bar member in operative gripping engagement with the rail but adapted when the anchor is being applied to the rail to yield for permitting the bar member to swing downwardly slightly for movement transversely of the rail into effective engagement therewith. 35
14. In a rail anchor, the combination of an abutment member in the form of a U having notches in the edges of both legs adapted to grip the flange of a rail and having an arm formed integrally with one of said legs in the form of a loop extending longitudinally of the rail toward the other leg, and a transverse bar member adapted by engagement with said abutment member and with said flange to hold said abutment member in operative gripping position on the flange, the engagement between said transverse bar member and said abutment member being effected through the medium of a turned back end portion of said bar providing a loop engaging about the loop on said abutment member adapted normally to hold said bar member up in operative position with respect to the rail but adapted upon compression of said first named loop to permit a slight downward swinging movement of said bar with respect to the abutment member. 40
15. In a rail anchor, the combination of an abutment member adapted to grip the flange of a rail at one side thereof, and a transverse bar member adapted by engagement with said abutment member and with said flange to hold said abutment member in operative gripping position on the flange, said transverse bar extending underneath the rail and across the top face of a portion of the abutment member positioned longitudinally of the rail below the level of the rail and extending thence downwardly and then backwardly in the form of a loop along the outer edge and the bottom face of said portion of the abutment member so as to be held normally by engagement with the abutment member also in effective engagement with the rail. 45
16. In a rail anchor, the combination of an abutment member adapted to grip the flange of a rail and comprising a part yieldingly movable transversely of the rail with respect to the major portion of the abutment member but adapted strongly to resist such transverse movement, and a transverse bar member having an end portion turned backwardly on the bar for providing a loop adapted to engage about said yieldingly movable part on said abutment member, said bar member being adapted by such engagement with said yieldingly movable part and with the edge of the flange at the opposite side of the rail to hold said abutment member in operative gripping position on the rail, said bar member being of such effective length as to hold the abutment member in operative gripping position on a rail of a predetermined minimum size with said yieldingly movable part in substantially normal position and to hold said abutment member in operative gripping position on a rail of slightly greater size with said yieldingly movable part moved transversely of the rail slightly out of normal position, said turned back portion of said transverse bar member being held by engagement with said abutment member from swinging vertically away from the bar member whereby 50
- 55
- 60
- 65
- 70
- 75

said loop is kept from spreading and thus loosening with respect to said abutment member.

17. In a rail anchor, the combination of a jaw member adapted to have gripping engagement with the flange of a rail when moved transversely of the rail into operative position thereon, means comprising an arm connected with said jaw member in position to extend longitudinally of the rail and adapted to be displaced from normal position upon application of the anchor to a rail and adapted by such displacement to swing said jaw member about an axis extending transversely of the rail for establishing a lever grip by said jaw member on the top and bottom faces of the rail flange, and a transverse bar member adapted by engagement with said arm and with the flange at the opposite side of the rail to hold said jaw member from backing transversely of the rail out of operative gripping engagement therewith.

18. In a rail anchor, the combination of a jaw

member adapted to have gripping engagement with the flange of a rail when moved transversely of the rail into operative position thereon, an arm on said jaw member in position to extend longitudinally of the rail therefrom, and a transverse bar member having an end portion turned backwardly on the bar for forming a loop adapted to engage about said arm and adapted by engagement with said arm and with the flange at the opposite side of the rail to hold said jaw member in operative gripping position on the rail, said transverse bar member and said arm being forced downwardly from normal position when said jaw member is moved into gripping position on the rail serving to swing said jaw member slightly about an axis extending transversely of the rail for giving said jaw member a lever grip on the top and bottom faces of the rail flange.

ROLANDIS A. BLAIR. 20
